UNITED STATES PATENT OFFICE.

RICHARD J. SICKELS, OF ARLINGTON, NEW JERSEY.

DESIGN FOR A FRAME FOR MIRRORS AND THE LIKE.

SPECIFICATION forming part of Design No. 25,076, dated January 21, 1896

Application filed August 26, 1895. Serial No. 560,602. Term of patent 7 years.

To all whom it may concern:

Be it known that I, RICHARD J. SICKELS, a citizen of the United States, residing at Arlington, New Jersey, have invented and produced a new and original Design for Mirrors, Trays, and the Like, of which the following is a description, referring to the accompanying drawings, which form a part of this specification.

10 In the drawings, Figure 1 is a face view, and Fig. 2 a sectional view, of a mirror-frame embodying my design.

15 The leading or characteristic feature of my design consists of a frame for mirrors and the like wherein the border projects from the body portion in a wavy crinkled flange of irregular elevations and depressions, the crink-

ling, ruffling, or crumpling being greatest at the inner edge of the border or frame and running into broadening surfaces toward the outer edge, as is clearly shown in the drawings. This characteristic is independent of the mirror or the like article.

I claim—

The design for a mirror-frame, or the like, substantially as illustrated and described.

In testimony whereof I have hereunto set my hand, at the city of New York, this 23d day of August, A. D. 1895.

RICHARD J. SICKELS.

In presence of—

H. S. CHAPMAN,
W. L. HEBBERD.
